UNITED STATES PATENT OFFICE.

PHILIP K. WILLIAMS, OF GLASTONBURY, CONNECTICUT, ASSIGNOR TO THE J. B. WILLIAMS COMPANY, OF GLASTONBURY, CONNECTICUT, A CORPORATION OF CONNECTICUT.

DESIGN FOR A TOILET-POWDER RECEPTACLE.

Application filed December 15, 1922. Serial No. 4,604. Term of patent 14 years.

To all whom it may concern:

Be it known that I, PHILIP K. WILLIAMS, a citizen of the United States, and a resident of Glastonbury, in the county of Hartford and State of Connecticut, have invented a new, original, and ornamental Design for Toilet-Powder Receptacles, of which the following is a specification, reference being had to the accompanying draw-

ing forming part thereof, in which the figure is a view in elevation of a toilet powder receptacle showing my new design.

I claim:

The ornamental design for a toilet powder receptacle, as shown in the accompanying drawing.

PHILIP K. WILLIAMS.
